CANADA, A CORPORATION OF CANADA.

ELECTRICAL HEATING-FURNACE.

1,279,313.

Specification of Letters Patent. Patented Sept. 17, 1918.

Application filed May 10, 1918. Serial No. 233,621.

To all whom it may concern:

Be it known that I, HERMAN V. FINNIE, a subject of the King of England, and a resident of St. Catharines, in the Province of Ontario, Canada, have invented certain new and useful Improvements in Electrical Heating-Furnaces, of which the following is a specification.

My invention relates to improved method and apparatus for electrically heating tubular structures, such as pipes, shells, or the like, and is of particular utility in the manufacture of ammunition shells for heating the ends thereof preparatory to nosing or coning of the ends.

Steel ammunition shells are usually first drawn out to cylindrical form whereafter the end is heated to permit nosing thereof in suitable dies. Several methods have heretofore been employed for heating the shells, one method consisting in dipping the shell to the required depth in a bath of molten lead, and by another method heating of the shell was accomplished by a flame, usually from an oil burner, localized to the section to be heated. These methods are objectionable, the use of lead being now prohibited in connection with the manufacture of high explosive shells on account of dangerous conditions that are set up when lead adhering to the shell comes in contact with high explosives. Also, both the lead process and the flame process form a scale, which is objectionable. Furthermore, heating by lead or flame is not uniform, the outer and inner surfaces of the shell being heated more highly than the inner portions of the mass, and the heating also takes so long that the bases of the shells become so hot that the shells cannot be handled directly but special apparatus or insulating material is necessary.

In general, the object of my invention is to electrically treat shells or other tubular structures in such manner that they will be rapidly and uniformly heated, and the heat confined to the desired zone so as to leave the outer end of the shell cool enough to be readily handled by workmen with their bare hands after the heating operation. More in detail, the main feature of the invention is the co-operation of a shell or other tubular structure with the core and primary winding of an electrical transformer in such man-

ner that the shell or tube when inserted will constitute a secondary short-circuited winding so that the heavy current flow therethrough will rapidly and uniformly heat it locally to the desired temperature. Another feature of the invention is such co-operation of the shell or tube that when applied to the transformer it will form part of, or complete, the magnetic circuit of the core structure, the magnetic energy being then utilized to accurately position the shell or tube so that the desired zone only will be subjected to heating.

On the accompanying drawings I show apparatus which I have found to be very efficient for carrying out the features of my invention. On these drawings—

Figure 1 is a front elevational view of the shell heating transformer structure and the support therefor,

Fig. 2 is a sectional view on plane 2—2, Fig. 1,

Fig. 3 is a sectional view on plane 3—3, Fig. 1, and

Fig. 4 is a sectional view on plane 4—4, Fig. 2.

Describing first the transformer structure, a rectangular core 5 built up of laminations, in the usual manner, has the opening 6 through one of its long sides and the opening 7 in the opposite long side and concentric with the opening 6. A core section or tongue 8, also laminated, is inserted through the opening 6 to project through the opening 7, the opening 7 being of larger diameter than the core section 8 to leave the annular space or gap 9.

P represents the primary or exciting winding having the leads 10 and 11 whereby it may be connected to receive alternating or pulsating current therethrough. Preferably the winding is built up of a number of circular units or coils 12 separated by spacing and ventilating strips 13, the built-up winding being inserted in the rectangular transformer core frame to be concentric with the core section 8. A bushing 14 of heat insulating material is preferably inserted in the winding and is of sufficient inner diameter to leave the annular space 15 around the core section 8. If, now, while an exciting current is flowing through the primary winding, a tubular structure *t*, such as a

shell, is inserted through the gap 9 into the space 15 surrounded by the primary winding, this shell section within this space will constitute a closed short-circuited secondary 5 winding or turn and the consequent heavy current flow through this shell zone will quickly heat it to a high temperature. The diameters of the core section 8 and that of the opening 7 are such relative to the inner 10 and outer diameters of the shell that the shell cannot short circuit the laminations. When the shell is inserted through the opening 7 it will form part of the magnetic circuit and practically close the annular gap 9 15 and the magnetic flow will be as indicated by the arrows, the magnetic lines of force passing lengthwise through the shell zone within the space 15, the heavy current flow being thus induced in this zone to heat it. 20 The bushing 14 protects the primary winding P from the intense heat generated in the shell.

Describing now the mechanical apparatus for supporting the transformer structure, 25 front and rear clamping frames 16 and 17 are provided, these frames being of rectangular box shape and having lugs 18 and 19 respectively at their ends for receiving bolts 20 for drawing the frames together. The 30 frame 16 has the opening 21 in line with the opening 7 of the core frame, while the clamping frame 17 has the opening 22 in registration with the opening 6 for the core section 8. Ridges 23 and 24 are formed on 35 the inner sides of the clamping frames for engaging with the edges of the core frame when the clamping frames are drawn together, the core frame laminations being preferably split, that is, right and left 40 halves, in order to overlap. The core frame is first assembled and then the primary winding coils and spacing strips inserted within the core frame and the clamping frames are then applied and the bolts 20 45 tightened so that the transformer frame and the coils and spacing strips are securely clamped together. Threading through the top and bottom walls of the clamping frames are screws 25 which engage against 50 the core frame at various points to clamp the laminations rigidly together. As the core section 8 is subjected to the heat of the tube or shell it is preferably removable so that it can be turned around or a new core 55 section applied. This core section is inserted through the opening 6 of the transformer frame and is then held in place by upper and lower clamping screws 26 and 27 threading through the upper and lower walls of 60 the clamping frame 17 and clamping the laminations of the core frame against the core sections, as clearly shown in Fig. 2. When the parts are thus securely clamped together the primary winding is concentric 65 with the core section 8 and the opening 21

is in line with the core opening 7 for the insertion of the shell to be heated.

The transformer structure is preferably mounted to be readily accessible and a number of such structures may be mounted in a 70 row. As shown, supporting pipes 28 extend upwardly from a base 29 for receiving U-bolts 30 which extend through the upper and lower brackets 31 and 32 on the front clamping frame 16 to be engaged by nuts 33. The 75 transformer structure can thus be secured at any height on the pipes 28.

Supporting means are also provided for guiding a shell into the transformer structure and for holding it in proper position 80 with reference to the various openings, and away from the core structure laminations. A bracket 34 is secured against the front wall of the clamping frame 16 by screws 35 and forms the V-shaped trough 36 for supporting the shells and guiding them centrally through the core opening 7 and into the space 15. The transformer arrangement is such that when a shell or tube of steel is inserted the polarity conditions will be such 90 as will tend to shift the shell or tube outwardly after it has been fully inserted. This is taken advantage of to automatically obtain the proper locating of the shell or tube within the transformer so that only the desired 95 zone will be heated. A U-shaped latch frame 37 is pivoted on lugs 38 and 39 extending laterally from the trough 36, and threading through the yoke of this latch is a set screw 40 against which abuts the outer 100 end of the shell or tube to be heated. The shell or tube is first pushed way into the transformer and the latch raised. Upon release of the shell the magnetic forces will shift it outwardly against the abutment 105 screw 40 which has been set so that after engagement thereof by the shell the inner end of the shell will be heated the desired distance. A spring 41 anchored to the bracket 34 and connecting with the inner 110 end of the latch frame tends to hold the latch frame in horizontal position with its inner ends against the abutments 42 and with the set screw 40 in position to receive the shell. To enable the latch frame to be 115 readily swung away when a shell or tube is to be inserted it is connected by a rod 43 with a foot lever 44 secured at 45 to the base 29. The foot lever is shown of spring material to be normally held up. When a shell 120 is to be inserted the foot is applied to the foot lever and the latch frame is swung down away from the trough 36, and after a shell has been inserted the foot lever is released whereupon the spring action of the 125 foot lever together with the force of spring 41 will restore the latch frame to its locking position. With the arrangement described a row of transformer structures can be quickly and accurately fed with shells or 130

other structures to be heated, these structures, after insertion, automatically being magnetically set in proper position to be heated at the desired zone, and after heating a step on the foot lever releases each shell for quick removal by hand.

The insulating and ventilating spacers 13 between the coils of the primary winding leave vertical ventilating passageways 10 through which air can circulate to keep the primary winding cool. To increase the flow of air through the passageways and around the coils upper and lower housing shells 46 and 47 are secured to the clamping frames, 15 the upper shell having the air inlet 48 and the lower shell the outlets 49. Air can be thus forced through the inclosure around the windings and over-heating prevented.

My invention is of general utility for 20 heating tubular structures or sections of other structures which are closed so that they can form a closed secondary circuit when applied to the transformer, and heating can be for the purpose of tempering, expanding, 25 forming or even welding, the uniformity, rapidity, localization and cleanliness of the heating being particularly useful and desirable. This is particularly true in the manufacture of shells where accuracy and 30 speed are so essential.

Without limiting myself to the exact construction, operation and procedure shown and described, changes and modifications still within the scope of the invention being 35 possible, I claim as follows:

1. In a heating furnace, the combination with a transformer core having a primary energizing winding thereon and having a gap, said core having a space for receiving 40 a tubular structure, said gap and space being so positioned that when the tubular structure is applied to said space it will form a closed secondary circuit and will close said gap.

45 2. In an electrical heating furnace, the combination of a transformer core, a primary winding thereon, a section of said core being surrounded by said winding and separated therefrom to leave an annular space 50 for the reception of tubular structures to be heated.

3. In an electrical furnace, the combination of a transformer core having an opening at one side, a core section extending 55 from the other side in line with said opening, a primary winding on said transformer core, said opening permitting the application to said core section of a tubular structure to be heated by forming a closed secondary turn.

4. In an electrical furnace, the combination of a rectangular transformer core having an opening at one side, a core section extending from the other side through said 60 opening to leave an annular gap, a primary

winding surrounding said core section and spaced away therefrom to leave an annular space in line with said gap for receiving a tubular structure to be heated, the tubular structure when inserted through said annular gap and into said annular space acting as a closed primary winding to be thereby subjected to heavy heating current flow.

5. In an electrical furnace, the combination of a rectangular transformer core having an opening at one side, a core section extending from the other side through said opening to leave an annular gap, a primary winding surrounding said core section and spaced away therefrom to leave an annular space in line with said gap for receiving a tubular structure to be heated, the tubular structure when inserted through said annular gap and into said annular space closing said magnetic gap and its section within 85 said annular space forming a closed secondary circuit for carrying heavy induced current flow when said primary winding is connected to a suitable source of electrical energy.

6. In an electrical furnace, the combination of a transformer frame having an opening at one side, a core section extending from the other side of said frame in line with said opening, and a primary winding 95 surrounding said core section and spaced away therefrom to leave an annular space in line with said opening into which space a tubular structure may be inserted by way of said opening to form a closed secondary 100 turn for receiving heating current flow.

7. In a shell heating furnace, the combination of a core, a primary winding surrounding said core and separated therefrom by an annular space, and magnetic return branches 105 extending from one end of said core to within a short distance of the other end thereof to leave a gap in line with said annular space, said gap and space serving to receive a shell for completing the magnetic return circuit and for forming a closed secondary turn to be thereby subjected to heavy induced current flow.

8. The combination with a transformer frame having a primary energizing winding 115 thereon and having a gap, of a tube inserted in said gap to complete the magnetic circuit and associated with a section of said core to be linked by the magnetic lines of force to thereby constitute a closed secondary turn.

9. In an electrical furnace, the combination of a rectangular transformer core having an opening through one side and a tongue extending from the opposite side into said opening to leave an annular gap, and a primary winding on said core concentric with said tongue and spaced away from said tongue to leave an annular chamber in line with said annular gap, said gap and chamber serving to receive a shell whose end will con- 120 125 130

stitute a closed secondary turn to be linked by the lines of force to be thereby heated by the inducer current flow therethrough.

10. In an electrical furnace, the combination of a transformer core having an opening through one side and a tongue extending from the other side into said opening to leave an annular gap, a primary winding on said core surrounding said tongue and spaced from said tongue to leave an annular space in line with said annular gap, a support in front of said gap for supporting shells concentrically in said gap and said space, the inner end of an inserted shell acting as a closed secondary turn to be heated by the induced current flow therethrough.

11. In an electrical furnace, the combination of a transformer core having an opening through one side and a tongue extending from the other side into said opening to leave an annular gap, a primary winding on said core surrounding said tongue and spaced from said tongue to leave an annular space in line with said annular gap, a support in front of said annular gap for shells to be heated, an adjustable stop on said support for holding a shell thereon with its inner end extending the desired distance into said annular space, such inner end constituting a closed secondary turn around said tongue to be linked by the lines of force through said core and to be highly heated by the induced current flow therethrough.

12. In an electrical furnace, the combination of a transformer core having an opening through one side and a tongue extending from the other side into said opening to leave an annular gap, a primary winding on said core surrounding said tongue and spaced from said tongue to leave an annular space in line with said annular gap, a support along which a shell can be inserted through

said annular gap and into said annular space to be concentric therewith, the shell when inserted setting up polarity conditions which tend to force the shell outwardly after insertion thereof, and an adjustable stop on said support for receiving the shell and for holding it in position with its inner end extending the desired distance into the annular space, said inner end forming a closed secondary turn which is linked by the magnetic lines of force and heated by the induced current flow therein.

13. In an electrical furnace, the combination of a transformer core having an opening through one side and a tongue extending from the other side into said opening to leave an annular gap, a primary winding on said core surrounding said tongue and spaced from said tongue to leave an annular space in line with said annular gap, a clamping frame surrounding and clamping together said transformer, core and primary winding, said frame having a passageway in line with said annular gap and annular space, a supporting and guiding bracket for shells to be heated secured to said frame, a shell when inserted through said annular gap and space being held concentric therewith by said bracket, the inserted shell completing the magnetic circuit and the resulting polarity conditions tending to shift said shell outwardly after insertion thereof, and an adjustable abutment on said bracket for receiving the outer end of said shell to hold its inner end the required distance in said annular space, such inner end forming a closed secondary turn linked by the magnetic lines of force and heated by the induced lines of current flow throughout.

In witness whereof, I hereunto subscribe my name this 1st day of May, A. D., 1918.

HERMAN V. FINNIE.
